UNITED STATES PATENT OFFICE

ANDERS JOSEF JONSSON, OF LINKOPING, SWEDEN.

CAPPING MACHINE.

Application filed May 25, 1925, Serial No. 32,759, and in Sweden June 14, 1924.

The closing of bottles and the like by means of caps has been made hitherto essentially after two lines. Either the cap has been produced separately in one or more machines and it has been applied to the neck of the bottle in a separate machine, or all operations have been executed in one and the same machine. The method last mentioned has afforded a considerable simplification of the work with the advantages resulting therefrom, but in the form as used it is also impaired by considerable inconveniences as is to be seen below. The machines for performing the said method are adapted to bend the blank directly on the neck of the bottle, that is to say, the neck of the bottle serves as a mandrel in the bending operation. The blank is stamped out over the mouth of the bottle, generally from a strip, and then it is immediately bent and tightened round the neck of the bottle. However, this method has proved to be anything but practical, especially because one is not able, on account of the different width and shape of the necks of the bottles, which are for the rest quite equal, to obtain the exact accordance between the neck of the bottle and the stamp which is necessary in corresponding members of bending tools of the said type, if the plate is to be free from folds and other unevennesses. Consequently, the caps are imperfectly bent and tightened round the necks of the bottles and the bottles are badly closed.

Another inconvenience of the method mentioned above lies in the fact that it does not admit any packing material in the shape of leaves, as for instance cork-leaves, to be inserted in the cap. The packing material is stamped out from a strip at the same time as the cap blank and by the same tools. For this reason it forms only a lining in the cap and cannot do the same service as the leaves which act almost as packing material.

This invention has for its object to obviate the said inconveniences by enabling the caps to be produced and applied to the neck of the bottle in one series and in one machine but by using separate tools for the operation, so that the cap is produced by one tool, the packing material, where this is to be used, is inserted in the cap by another tool and the capping operation is made by a third tool. By the operations being distributed to separate tools it is possible to perform them with a

precision quite inconceivable in the older machines and one will still reach the same speed of the work. The problem which this invention has for its object to solve does, however, not consist in the said tools being collected in one and the same machine but in the method and the means for transferring the caps from one tool to the other in order that the machine may work quite automatically. This problem has been very difficult to solve by reason of the fragility of the caps and the difficulty of the conveyer or conveyers grasping them steadily. By this invention this problem has, however, been solved in the simplest and most practical manner, the cap engaging and carrying members or conveyers being adapted to displace pneumatically the caps finished or being made, for which purpose the conveyers communicate by a piping with a suitable suction device, as for instance a blast.

The manner in which this invention may be performed is to be seen from the following description and the accompanying drawing showing a capping machine which produces the cap and applies it to the neck of the bottle quite automatically.

Figure 1 is a front view of the machine,

Figure 2 is a side view,

Figure 3 is a plan view of the same,

Figure 4 is a side view,

Figure 5 is a plan view of the conveying means, and

Figure 6 is an enlarged fragmentary side elevational detail.

The stamping and bending tool 1 of the known construction, by means of which the blank is stamped out and bent is mounted in a slide-block 2 of the frame 3, the said tool being moved upwards and downwards as usual by a crank shaft 4 driven by an electric motor 50 or from another source of power. On the table 5 located under the tool 1 the strip 6 is fed step by step by a suitable device to and under the tool 1 from the roll 8 gradually as the blanks are being stamped out. The plate waste escapes through an opening 9 in the table.

The packing material, preferably cork, is mounted in the shape of round leaves in a vertical tube 10 provided beside the tool 1. Through the said tube the packing leaves slide successively down to the table 5 in front of a conveyer 11 which pushes the leaf under

a stamp 12. In this form the said stamp is fixed to an arm 13 projecting from the slide-block 2. The conveyer is mounted in the table for a reciprocating movement which is imparted to it by a pin fastened on the same and provided with a roll 14 engaging a curved groove of a suitable shape and provided in a disc 15 which is connected by gear to the motor and rotates always in one and the same direction during the running. The finished cap 56 is to be placed under the stamp 12 as shown in Fig. 6, thus in the position in which it leaves the stamping and bending tool 1 and is fastened on the neck of the bottle. Simultaneously, a cork leaf has been pushed under the cap. Then the stamp descends and places the cap just right above the packing leaf and a piston 16 acting from below and forcing the leaf into the cap which is thereby supported by the stamp 12. Motion is imparted to the piston 16 by a lever 17 located under the table 5 and actuated in its turn by a cam 18 on the lower side of the disc 15. After the packing leaf has been inserted in the cap the same is moved into the capping tool. As usual the said tool comprises a closing mouth-piece 22 with an inner piston 45 intended to press a ring 55 of elastic material located in the mouth-piece round the neck of the bottle in order that the cap may be tightened round the same. The bottle is placed on a supporting plate 20 movable in vertical direction so that it is able to push the neck of the bottle high enough into the mouth-piece 22. The supporting plate rests on an upright 21 located in the frame and movable in its longitudinal direction and connected with a two-armed lever 23 of the frame and actuated by an eccentric 24 driven by the motor by means of gear and a belt drive. The upright 21 is connected with the outer end of the lever 23 by links 7, one on each side of it. The inner end of the said lever is provided with a roll 25 which is pressed against the lower edge of the eccentric by the weight of the upright et cetera. Thus, the supporting plate is raised once for each revolution of the eccentric, the speed of which is adjusted in such a manner that the said movement takes place each time a cap is inserted in the closing mouth-piece. For adjusting the position of the raised bottle in relation to the elastic ring and the piston 45 respectively the plate 20 is shaped as a screw 26 which may be inserted for a greater or less distance into the upright 21. The bottles are moved successively to and from the supporting plate 20 as usual by means of a device working automatically and not shown here. The piston 45 is moved up and down by an one-armed lever 27, a link-rod 28, a cam-disc 29 and an eccentric 30. The lever 27 is mounted in a member 31 screwed on to the table 5. The cam-disc 29 and the eccentric 30 are fixed to the same shaft in the lower

portion of the frame and they co-operate with the link-rod 28 in such a manner as to allow the cam-disc 29 to lower the same and the piston 45, and the eccentric 30 to raise both members.

As is to be seen from the aforesaid this invention refers especially to a device for transferring pneumatically the caps from one tool to the other by movable members which grasp the caps by suction in a quite reliable manner and hold them during the transfer. The manner in which the conveyers may preferably be executed according to this invention is described below.

The conveyers consist here of two tubes 32, 33 extending like the spokes of a wheel from a hollow head 34 located on the table 5 and movable round a vertical shaft 48, and by the said head they communicate with a suction pipe 36 leading to a blast 35. From the head 34 extends an arm 37 provided with a roll 38 adapted to co-operate with a cam-disc 39 mounted on the disc 15. By means of the said cam-disc and a spring 47—an ordinary shackle-spring may also be used—the said tubes oscillate with equal intervals: the tube 32 between the stamps 1 and 12, the tube 33 between the stamp 12 and the mouth-piece 22 which is provided with an opening 40 (Fig. 5) for the insertion of the cap 56. The axes of the stamps 1 and 12 and of the mouth-piece are situated approximately at the same distance from the fulcrum of the conveyers 32, 33 and they have the same distance between them, the conveyers being so adjusted as to their length that when placed each in front of its tool they come very near to the cap located in or under the same. When the cam-disc 39 does not actuate the arm 37, the spring 47 keeps the conveyers in their extreme position shown in Figure 3 where the mouth of the conveyer 32 is situated opposite the stamp 12 and the mouth of the conveyer 33 is located in the mouth-piece 22. The conveyers work in the following manner:

During the running of the machine the blast rotates with great speed whereby a comparatively strong suction is produced at the mouths of the conveyers which are adjusted by the cam-disc 39 each in front of its tool 1 and 12 respectively immediately before the caps are displaced. At the very instant when the stamp 1 releases the cap the same is carried away by the air current and sticks at the mouth of the conveyer 32. In order that the cap may not be retained by the plate waste the mouth of the conveyer must be placed sufficiently high for the cap being raised from its position. Simultaneously, the cap in the tool 12, 16 has stuck to the conveyer 33. The spring 47 now swings the conveyers into the other extreme position and the caps held in the conveyers by the suction following. The former cap is placed under the stamp 12 and grasped by the stamp during the downward

movement of the latter for the insertion of the packing leaf. The latter cap provided with packing material is placed over the mouth of the bottle in the mouth-piece and 5 grasped by the bottle so that the neck of the latter during the upward movement of the bottle is put into the cap and then this cap is fastened to the neck of the bottle. Then the conveyers are swung back by the cam-10 disc as before and the course is repeated.

When producing and fastening caps without packing leaves one conveyor only is used which is adapted to transfer the cap from the stamping tool directly to the capping tool.

15 In order to prevent the cap from following the conveyor 33 back to the stamp 12, in case the supply of bottles is interrupted, the machine may be provided with an obstacle to the cap which is arranged so as to allow the 20 cap to be transferred from the stamp 12 but not back to it. The said obstacle may simply consist of a rigid wire, metal strip 51 or the like fixed to the arm 13. When the conveyor 33 is moved from the stamp 12 to the mouth-25 piece 22 the arm 13 occupies its upper position and holds the wire 51 out of the path of the cap. When the conveyor is returned to the stamp 12 the same is in its lower position and then holds the wire in the path of the cap. 30 Caps caught by the said obstacle fall down under the table 5 through an opening 41 in the same.

According to the nature of the invention the same may be applied in different manners 35 and the means for its performance may be varied in several respects without the idea underlying the same being given up.

Having now described my invention, what I claim as new and desire to secure by Letters 40 Patent is:

1. A capping machine including a tool for stamping a cap blank out of a strip and forming a cap, a tool situated laterally of the first tool for applying a cap to a bottle, pneumatic 45 cap engaging and carrying means for transferring a cap from one of said tools to the other, means for moving the engaging and

carrying means in timed relation with the tools and laterally adjacent the tools, whereby the engaging and carrying means will engage the side edges of the cap, substantially as and for the purposes set forth. 50

2. A capping machine including in combination, a tool for stamping a cap out of a strip and forming a cap, a tool for inserting 55 packing material into the cap, a tool for applying the cap to a bottle, said tools operating in the same direction and being situated at equi-distant points from each other, a plurality of pneumatic cap carrying engaging 60 members mounted for oscillatory movement with respect to the tools for engaging and transferring caps from one tool to the adjacent tools, and means for operating said cap engaging and carrying members independently of the tools. 65

3. A capping machine as claimed in claim 2, wherein each of the tools is vertically movable and wherein the cap carrying and engaging 70 members are tube shape and are mounted for horizontal swinging movement, whereby to facilitate the engagement of the members with the side edges of the cap during the transferring action.

4. A capping machine including a tool for stamping a blank out of a strip and forming a cap, a tool for applying caps to a bottle, said tools being constructed so that portions 75 of the skirt of each of the caps when engaged by the tools are left free, pneumatic conveying and carrying members operating in a plane at right angles to the direction of movement of the tools for transferring a cap from one tool to the other, and means for moving the cap engaging and transferring 80 means, whereby the latter will engage the free skirted portions of the cap when the caps are located on the tools to permit of a ready transferring of a cap from one tool to another, substantially as and for the purposes set forth. 85

In witness whereof, I have hereunto signed my name,

ANDERS JOSEF JONSSON.
